UNITED STATES PATENT OFFICE

JOHN L. OSBORNE, OF ROCHESTER, NEW YORK, ASSIGNOR TO GENERAL RAILWAY SIGNAL COMPANY, OF ROCHESTER, NEW YORK

COUNTERWEIGHT

Application filed November 7, 1928. Serial No. 317,874.

This invention relates in general to improvements in light signals, relays and the like for use in railway operation, and has more particular reference to means for minimizing the energy required for maintaining a rockable shaft in energized position, and for effectually preventing overrun of such shaft on movement from energized to de-energized position.

- 10 In relays and light signals it is usual to employ a rockable shaft biased to a neutral position and selectively energizable to move to a normal or reverse energized position. In moving the shaft to an energized position energy is required to overcome the bias caused by the biasing means, while upon de-energizing the device, the shaft is moved to neutral position and tends to overrun beyond the neutral position due to acquired momentum.
- 15 It is of course desirable to use as little energy as possible to properly move the shaft to energized position, and it is also desirable to prevent as largely as possible any overrun of the shaft, as the same causes opening and closing of contacts in a relay or flashing of a signal indication in a light signal.

With the above and other objects in view it is proposed, in accordance with this invention, to provide a counter-weight for effectually accomplishing the above set forth desirable functions. More specifically, the shiftable counter-weight of this invention comprises a casing having a partition dividing it into two chambers with a passageway between the two chambers, whereby mercury or the like in the casing can transfer from one chamber to another by gravity. Due to movement of the casing which is fixed to rock with the shaft, the mercury transfers from one chamber to another in a manner to minimize the energy required to hold the shaft in energized position, and upon de-energization, the mercury is already positioned so as to effectually prevent undue overrun beyond de-energized position.

Further objects, purposes and characteristic features will appear as the description progresses, reference being had to the accompanying drawings, showing, solely by way of example, and not in any manner in a

limiting sense, one form which the invention can assume. In the drawings:

Fig. 1 is a side elevation of one embodiment of the invention, with parts shown in section.

Fig. 2 is a front elevation of the invention.

Fig. 3 is a sectional view of the shiftable counter-weight, taken on line 3—3 of Fig. 4.

Fig. 4 is a side elevational view of the shiftable counter-weight.

Figs. 5—8 inclusive are diagrammatic views showing various operative positions of the shiftable counter-weight.

Referring now to the drawings, a spindle 1 is pivoted in any desired or usual manner so as to rock about a horizontal axis. Sleeved on the spindle 1 is a sleeve member 2 fixed to spindle so as to rotate therewith, the sleeve member including a fixed counter-weight 3 and a bracket member 4. Connected to the bracket member 4 by rivets or the like 5 is a usual spectacle 6 equipped with different colored glasses 7, 8 and 9, as yellow, red and green respectively, for giving distinctive signal indications. Fastened to the member 4 is a usual vane 10 arranged to cooperate with field members, not shown, whereby it can be operated so as to rock spindle 1 either clockwise or counter-clockwise from the position shown in Fig. 2, whereby to interchange the positions occupied by the different glasses 7—9 carried by the spectacle so as to give various indications.

The operation of the vane 10 and of the spectacle 6 can be such, for example, as occurs in the patent to W. D. Hailes 1,617,247 February 8, 1927, the patent to Carter 1,667,469 April 24, 1928, and the applications of Merkle and Field respectively, Ser. Nos. 132,835 filed August 31, 1926, and 128,437 filed August 10, 1926.

The shiftable counter-weight of this invention, as best shown in Fig. 3, comprises a casting C having an inner partition 11 separating the interior of the casting into two chambers 12 and 13, a passage 14 being formed in the partition in its lower portion and a passage 15 being formed in its upper portion, whereby mercury or like heavy liquid, placed in the chambers 12 and 13, can readily transfer from one chamber to said other chamber.

under the force of said gravity through passage 14, while the passage 15 prevents the device from becoming air bound.

In the partition 11 is a hole 16 for receiving the end of spindle 1, and a hole 17 for receiving a screw or the like 18 for fastening the casing C rigidly to the member 4 whereby the casing C, the sleeve 2, and the spindle 1, the weight 3 and the spectacle 6 all 10 rock together under the influence of the vane 10.

As shown in Fig. 3, the casing C, preferably cast, is formed with two openings 19 and 20 for removing the cores after which 15 these openings are sealed by plugs 19¹ and 20¹ which are fixed in place by welding or the like, the plug 20 having a drilled hole 21 therein through which mercury is poured into the chamber 12 and 13, the hole 21 then 20 being plugged up in any suitable manner. The passage 14 in the partition 11 is formed by drilling the same through the casing C, the resulting hole 22 in the casing being thereafter sealed by a pin 23 which is welded 25 or otherwise retained in place.

With the parts as shown in Fig. 2, the spectacle 6 is positioned to have the glass 8 in the path of light from a light source (not showing) whereby to give a signal indication, 30 such as red, for indicating stop. The various parts connected to the spindle 1 are so proportioned that there is only a very slight bias on the spindle 1 to the de-energized position, as shown in Fig. 2, the vane 10, 35 counter-weight 3 and shiftable counter-weight just slightly over-balancing the spectacle 6 and the member 4.

On energization of the device so as to rock the spindle and casing C counter-clockwise, 40 for example, as viewed in Fig. 3, the mercury in chamber 12 is transferred under the force of gravity into chamber 13 through passage 14. As shown diagrammatically in Figs. 5-8, as casing C moves from its de-energized 45 position D, as shown in Fig. 5, to normal energized position N, as shown in Fig. 6, the mercury does not immediately run out of chamber 12, since the aperture 14 is too small to permit this. As soon, however, as vane 10 50 has reached its normal position, the mercury quickly transfers from chamber 12 into chamber 13 so as to bring about the condition shown in Fig. 7 where practically all of the mercury is in the chamber 13, which chamber 55 13, it will be noted, lies closer to the vertical axis D (passing through the de-energized position) than does chamber 12, and, hence does not exert as large a torque tending 60 to rock shaft as it would if positioned partly 65 in chamber 12 back to de-energized position. As a result, less energy is required to maintain the spindle in its normal position, than would be required if a fixed counter-weight were used, so in which event the weight distribution would have to remain as shown in

Fig. 6 (i. e., not subject to a shift from chamber 12 to chamber 13).

Upon de-energization of the device, the mercury which is all in chamber 13, as shown in Fig. 7, exerts a bias on the spindle 1 toward de-energized position. As the spindle rocks clockwise, the center gravity of the mass of mercury in chamber 13 reaches a position vertically below the axis of rotation, before the vane and spectacle have reached 70 de-energized position, by an amount equal to the angle α as indicated in Fig. 8, the size of angle α depending on the proportioning of the various parts. From the position I shown in Fig. 8, the mercury in chamber 13 exerts a retarding effect on further movement of the parts to the left, and hence prevents a large overrun to the left past position D, since the retarding effect is brought into action 75 considerably before (by amount of angle α) the spindle and connected fixed parts have reached de-energized position (D).

The passage 14 in partition 11 is so proportioned that on de-energization, the spindle 1 reaches the position I, indicated in Fig. 8, before any appreciable amount of mercury has been transferred back into chamber 12 from chamber 13, but the passage 14 is large enough so that immediately after reaching such position I (Fig. 8) a transfer of mercury quickly takes place from chamber 13 into chamber 12 to shortly reach the condition shown in Fig. 5, and thus bring the spindle to rest in de-energized position D, with 80 very little overrun.

On energizing the device to the reverse position (R) the same operation, in reverse direction, takes place as described above.

It is thus seen that with the shiftable counter-weight, the center of gravity of the weight shifts relatively to the spindle 1 in such a manner that on energization, it shifts toward the de-energized position D, when the spindle is moved to either the normal position N, or the reverse position R, to thereby exert a turning moment on the spindle toward de-energized position having an arm 24 which is considerably shorter than arm 25 which would be the effective arm if the counter-weight were not shiftable. In this manner less energy is required to hold the device in energized position than would otherwise be the case.

It is also apparent from the above that upon de-energization of the device, the spindle 1 is biased to de-energized position from either normal or reverse position, the mercury having shifted while in the energized position to be so disposed that the shiftable counter-weight reaches a position of stable equilibrium I before the spindle 1 reaches de-energized position to thereby initiate a retarding effect on overrun prior to the time when the spindle reaches its de-energized 120 position D.

It is of course within the scope of this invention to vary the amount of mercury employed, and the proportioning of the various parts, including the size of the passage 14, whereby various effects can be produced. It is thought preferable however to have the parts proportioned as set forth above so that, on movement of the spindle from energized to de-energized position, at least only a small amount of mercury will transfer from one chamber to the other before the spindle reaches the overrun preventing initiating position I, as indicated in Fig. 8, at which position a braking effect is initiated on overrun of the spindle.

The above rather specific description of one form of the present invention is given solely by way of illustration, and is not intended, in any manner whatsoever, in a limiting sense. Obviously, the invention can assume many different physical forms, and is susceptible of numerous modifications, and all such forms and modifications are intended to be covered by this application, as come within the scope of the appended claims.

Having described my invention, I now claim:—

1. In a light signal, in combination, a spindle pivoted to rock on a horizontal axis from a pendent, de-energized position indicating danger, to an energized position, and a counter-weight movable with said shaft and capable of shifting the center of gravity of its mass toward said axis upon movement of said spindle to energized position, said counter-weight, when at rest in pendent position, being in stable equilibrium, but upon moving from said energized position toward said pendent position, reaching a position of stable equilibrium before reaching said pendent position, whereby to effectually damp oscillations and minimize overrun to thus prevent momentary losing of a danger indication.

2. In a light signal, in combination, a spindle pivoted to rock on a horizontal axis from a pendent, de-energized position, to an energized position, and a counter-weight movable with said shaft and capable of shifting the center of gravity of its mass toward said axis upon movement of said spindle to energized position, said counter-weight, when at rest in pendent position, being in stable equilibrium, but upon moving from said energized position toward said pendent position, reaching a position of stable equilibrium before reaching said pendent position, whereby to effectually damp oscillations and minimize overrun, said counter-weight including, a casing fixed to rock with said spindle, separate chambers in said casing interconnected through a constricted opening, and a body of liquid in said casing and free to move from one chamber to the other under the force of gravity.

3. In light signals and like devices, in combination, a spindle pivoted to rock on a horizontal axis from a pendent, de-energized position, to an energized position, and a counter-weight movable with said shaft and capable of shifting the center of gravity of its mass toward said axis upon movement of said spindle to energized position, said counter-weight, when at rest in pendent position, being in stable equilibrium, but upon moving from said energized position toward said pendent position, reaching a position of stable equilibrium before reaching said pendent position, whereby to effectually damp oscillations and minimize overrun, said counterweight including, a casing fixed to rock with said spindle and depending therefrom, a central partition in said casing dividing the interior thereof into two chambers situated respectively at opposite sides of a vertical line through said spindle, when in the pendent position, a constricted opening in said partition at the lower end of the same, and a body of mercury in said chambers free to pass from chamber to chamber under the force of gravity.

4. In a light signal, in combination, a spindle pivoted to rock on a horizontal axis from a pendent, de-energized position indicating danger, to an energized position indicating a relatively unrestrictive condition, and a counter-weight movable with said shaft and capable of shifting the center of gravity of its mass toward said axis upon movement of said spindle to energized position, said counter-weight, when at rest in pendent position, being in stable equilibrium, but upon first moving from said energized position toward said pendent position, reaching a position of stable equilibrium before reaching said pendent position, whereby to effectually damp oscillations and minimize overrun and prevent momentary losing of a danger indication, said counter-weight including, a casing fixed to rock with said spindle and depending therefrom, a central partition in said casing dividing the interior thereof into two chambers situated respectively at opposite sides of a vertical line through said spindle, when in the pendent position, a constricted opening in said partition at the lower end of the same, and a body of mercury in said chambers and free to pass from chamber to chamber under the force of gravity, an aperture through the upper part of said partition connecting said chambers to allow the passage of air, and means fixing said casing to said spindle.

In testimony whereof I affix my signature.

JOHN L. OSBORNE. 125
